C. HOFFMAN

DOOR FASTENER

Filed Aug. 11, 1923

FIG. 1.

FIG. 3.

FIG. 2.

Inventor.

CARL HOFFMAN

By his Attorney

UNITED STATES PATENT OFFICE.

CARL HOFFMAN, OF ALLENTOWN, PENNSYLVANIA.

DOOR FASTENER.

Application filed August 11, 1923. Serial No. 656,851.

To all whom it may concern:

Be it known that I, CARL HOFFMAN, a citizen of the United States, residing at Allentown, in the county of Lehigh and State 5 of Pennsylvania, have invented certain new and useful Improvements in Door Fasteners; and I do hereby declare the following to be a full, clear, and exact description of the invention, such as will enable others skilled in 10 the art to which it appertains to make and use the same.

This invention relates to door fasteners and particularly to a fastener adapted for locking a door in either closed or partially 15 open position.

An object of this invention is to provide a latch and keeper for a door and jamb to lock the door in closed position and to secure an operating means to the latch adapted for 20 locking cooperation with the keeper to fasten the door in partially open position.

Another object of the invention is to provide a latch and keeper for a door and jamb to lock the door in closed position and an 25 operating member for the latch adapted for association with an auxiliary latching means carried by the keeper for fastening the door in partially open position.

A further object of this invention is to 30 provide a latch rotatably mounted on a jamb adapted for engagement with a keeper plate secured to a door, the latch being provided with an arm pivoted thereto acting as a handle for operating the latch and being further 35 provided with an auxiliary keeper adapted for association with a pivoted member carried by the keeper plate which is adapted to secure the auxiliary keeper to said plate for locking the door in partially open position.

The invention includes further objects and 40 novel details of construction specifically pointed out in the following description and claims and shown in the accompanying drawings in which Figure 1 is a perspective view of the invention applied to a door and jamb with the parts positioned to fasten the door in partially open position. Figure 2 is a perspective view showing the door in closed 45 position and the parts being disengaged so that the door may be locked in closed position, and Figure 3 shows an elevation of the door and jamb with the parts positioned to lock the door in closed position.

50 1 indicates the door adapted to close in the jamb 2 which is provided with a plate 3

supporting a rotatable spindle 4 having a latch 5 formed therewith and projecting laterally therefrom. An elongated rod-like member 6 has one end pivotally connected 60 with the spindle 4 as indicated at 7 and the other end provided with an auxiliary keeper 8 projecting laterally therefrom and provided with an opening at 9.

A keeper plate 10 is secured to the inner 65 face of the door and is adapted to cooperate with the latch 5 to hold the door in closed position and take the wear of said latch. The keeper plate 10 is provided with a stud 11 to which is pivotally secured a guiding 70 and auxiliary locking member 12 which is adapted for insertion in the opening of auxiliary keeper 8 and for guiding said keeper in the opening movement of the door to a position shown in Figure 1 after which the member 12 is moved on its pivot to lie against the door as shown in Figure 1 for locking the door in partially open position and against a further opening or closing 75 movement. In order to insure retention of the member 12 in locked relation with the auxiliary keeper a catch 13 is rotatably mounted in the keeper plate 10 and is adapted to engage the member 12 and hold the 80 same in locking position.

85 Figure 2 shows the door with the parts in position as it is being closed from the partially open position in Figure 1 the rod 12 guiding the keeper 8 in the closing movement of the door. From this position the rod 12 is disengaged from the keeper 8 and is swung back against the door and secured in this 90 position by the catch 13 as shown in Figure 3 and the elongated member 6 is used as a handle for operating the catch 5 to rotate the same and bring it in engagement with the keeper plate 10 for locking the door in closed position. The progression from closed position, as shown in Figure 2, to the partially open position, as shown in Figure 95 1, in which the rod 12 interlocked with the keeper 8 has been moved on its pivot and secured against the door by the catch locking the keeper 8 therewith and holding the door in partially open position, is apparent.

100 It is to be noted that the parts illustrated in the drawing and above described are adapted for use with a door which opens inwardly the parts being shown secured to the inner face of the door and jamb.

105 I claim as my invention:

1. A door fastener including a door car-

ried element and a jamb carried element, one of said elements being movable for engaging the other to lock the door in closed position, operating means for the movable element, said operating means being adapted for engagement with the other element, and positive independently operable means for locking said operating means in engagement with the other element for locking the door in partially opened position.

2. A door fastener including a keeper, and a latch, one mounted on the door and the other on the jamb, and adapted for cooperation to lock the door in closed position, and an elongated member having pivotal connection with the latch for operating the same to engage or disengage it from the keeper, and latch means carried with the keeper for cooperating with the free end of the member for fastening the door in partially open position.

3. A door fastener including a keeper and a latch, one mounted on the door and the other on the jamb and adapted for cooperation to lock the door in closed position, an elongated member pivotally connected with the latch, means carried with the keeper having a sliding connection with the member from the closed position of the door to a partially open position thereof, and locking means associated with the keeper for locking the member therewith to fasten the door in a partially open position.

4. A door fastener including a keeper plate mounted on the door, a latch rotatable on the jamb adapted for engagement with the keeper plate to lock the door in closed position, an elongated member having one end pivotally connected with the latch adapted for operating said latch, an auxiliary keeper carried by the member and auxiliary latching means adapted for cooperative engagement with the auxiliary keeper for fastening the door in partially open position.

5. A door fastener including a keeper plate mounted on the door, a latch rotatable on the jamb adapted for engagement with the keeper plate to lock the door in closed position, an elongated member having one end pivotally connected with the latch adapted for operating said latch and provided at the other end with an auxiliary keeper, an auxiliary latching and guiding member pivotally mounted on the keeper plate adapted for sliding cooperation with the auxiliary keeper for guiding the same in opening movement of the door and for interlocking therewith to hold the door in partially open position, and a catch mounted on the keeper plate adapted for holding the auxiliary latching member in locking position.

In testimony whereof I have signed this specification.

CARL HOFFMAN.
